FISH TRAP STRUCTURE

Filed July 5, 1928

UNITED STATES PATENT OFFICE

WILLIAM G. HUME, OF PEORIA, ILLINOIS, ASSIGNOR TO KEYSTONE STEEL & WIRE COMPANY, OF PEORIA, ILLINOIS, A CORPORATION OF ILLINOIS

FISH-TRAP STRUCTURE

Application filed July 5, 1928. Serial No. 290,546.

This invention has reference to fish trap structures and it has for its principal object to improve the body of such structures; to provide improved means to strengthen the 5 selavage or marginal edges of the sections of the structure; to provide the structure with self contained means for supporting the weights of the structure and to prevent bulging of the structure at points from which the 10 weights are sustained and to make it possible to manufacture such structures at a considerably reduced cost than heretofore. This latter element is important when it is considered that structures of this character are 15 used, as a rule, only one season.

Fish traps of the character referred to are used particularly in the salmon industry.

Other and further objects will more fully appear from the following description.

20 That the invention may be more fully understood, reference is had to the accompanying drawings, forming part of this description, illustrating a preferred embodiment of the invention, in which:—

25 Fig. 1 is a vertical elevation of my improved fish trap structure, on a greatly reduced scale, and shows in a somewhat conventional manner and it might be said, diagrammatically, several sections of such a 30 structure connected together and to pilings and showing the reinforcing and weight-supporting means;

35 Fig. 2 is a detailed spot view showing enlarged, the character of the body of the fabric of the structure, the reinforcing means, manner of connecting adjoining selavage portions of adjacent sections and manner of connecting the weights to the reinforcing means;

40 Fig. 3 is a detail in plan, showing the manner of connecting selavage portions of adjoining sections of the structure, and

45 Fig. 4 is a detailed spot view showing enlarged, selavage portions of adjoining sections of the structure, reinforcing means and manner of connecting the sections to buoys in floating traps.

Like characters of reference denote corresponding parts thruout the figures.

50 A fish trap structure would embody a plurality of sections of fabric connected together

and sustained in proper position and relation by piling or by buoys. Therefore, a description of a section of fabric and the manner of connecting the same to adjoining sections and reinforcing same to sustain weights and to prevent bulging at weight sustaining points should suffice.

The fabric of my invention is preferably of square mesh and made in sections preferably six feet wide and seventy-two to ninety feet long with meshes two by four inches; the two inch meshes disposed vertically and the four inch meshes disposed horizontally. While it is desirable to understand the width and length of the sections of fabric constituting a structure, and to understand something of the size of the meshes, I do not desire to imply that these are limitations as I realize fully variations may be necessary to meet conditions from time to time. Also, 70 while the structure of Fig. 1 is shown sustained by pilings and weights and the structure of Fig. 4 is sustained by a floating structure and weights, these are not intended as limitations but merely illustrative.

The fabric is composed of longitudinal wires 1 and cross wires 2, so spaced as to produce the size meshes desired and I prefer that the cross wires 2 and the intermediate longitudinal wires 1 shall be of uniform 80 gauge and weight and preferably of the lighter gauges of wires, as compared with the longitudinal selavage or marginal wires, which I prefer shall be of a much heavier gauge and weight, as such wires provide, not only the 85 reinforcing means for the sections, but together with the selavage or marginal wires of adjacently placed sections provide strengthening ribs in the trap structure to sustain the same and additionally, to provide the sustaining means for the weights which are employed to hold the structure in proper vertical position in the water and against the movement of the water. Furthermore, I prefer that the wires 1 and 2 where they intersect 90 shall be staple connected, as at 3, and the cross wires 2 connected, at their ends, to the heavier marginal or selavage wires 1 by being wrapped or coiled thereabout, as at 4.

In the construction of a trap, whatever may 100

be its design, sections of fabric, such as I have described, and as illustrated in Fig. 1, are placed side by side and sustained in vertical position in the water, by either pilings A, Fig. 1, or by a floating structure, such as buoys B, Fig. 4, and in each instance the lower portions of the sections and structure which are unsupported or attached to permanent means, as for instance, pilings, are held in position and the sections of fabric taut and straight, by means of weights 5.

A stringer 6, of heavy gauge material or a cable is provided for the attachment thereto of the longitudinal wires 1, preferably by carrying the ends of such wires 1 thereover and then coiling or wrapping the ends of the wires 1 about themselves, see Fig. 4. Also, when the sections of fabric are assembled, the heavier marginal or selvage wires 1 of adjoining sections are connected by preferably "hog-rings" 7, see Figs. 2 and 4.

The weights are attached to and sustained from and by pairs of adjoining heavy marginal or selvage wires 1 of the adjacently placed sections of fabric, in the manner best seen in Fig. 2. Here it is shown that the sustaining means 8 of a weight 5 is threaded up between a pair of marginal or selvage wires 1, thru a "hog-ring" 7 and having connection with a similar superimposed "hog-ring". While I have shown this weight connection with the marginal or selvage wires, it is to be understood this mode of attachment may be modified, as occasion demands. It should be obvious, however, that by providing the heavy marginal or selvage wires, the fabric, as well as the assembled structure, is reinforced at these points and that such reinforcing means provides ample sustaining means for the connection and support of the weights for holding the fabric vertically taut and straight and that so held the marginal or selvage wires being connected by "hog-rings", bulging between the adjoining sections is prevented.

The stringer 6, provides the means of attaching the structure, at its upper portion to the pilings, see Fig. 1, and also the means for the attachment of the structure to a floating support, as for instance buoys, see Fig. 4.

Constructing the fabric of square meshes and tying the cross-wires where they intersect by staples, will prevent travelling or enlargement of any breaks in the fabric in the event of cutting by loose piling or from other causes.

What I claim is:—

A fish trap structure, comprising sections of wire fabric, each section made from a plurality of longitudinal and cross wires joined at their intersections to produce square meshes, the marginal longitudinal wires being sufficiently heavy to provide, when the sections are joined, reinforcing and strengthening ribs for the said structure, means

adapted for connection with the lower ends of pairs of marginal wires of adjoining sections for weighting down the said sections and to hold the same taut, rings connecting marginal wires of adjoining sections, and a stringer support for the structure to which are connected the longitudinal wires of each section.
